(57) **CLAIM**

The ornamental design for a filtration shirt, as shown and described.

DESCRIPTION

FIG. 1 is a front view of a filtration shirt showing the claimed design;

FIG. 2 is a back view of the filtration shirt thereof;

FIG. 3 is a left perspective view of the filtration shirt thereof, the right-side view being a mirror image of the left-side view;

FIG. 4 is a zoomed-in front view of the neck collar of the filtration shirt thereof;

FIG. 5 is a zoomed-in back view of the neck collar of the filtration shirt thereof;

FIG. 6 is a zoomed-in front view of the neck collar of the filtration shirt thereof, where the shirt is turned inside-out;

FIG. 7 is a zoomed-in back view of the neck collar of the filtration shirt thereof, where the shirt is turned inside-out;

FIG. 8 is a front view of the filtration shirt thereof with the neck collar deployed over the face of a wearer.

FIG. 9 is a back view of the filtration shirt thereof with the neck collar deployed over the face of a wearer; and,

FIG. 10 is a front view of the filtration shirt thereof with the neck collar, undeployed.

The dot-dash lines define the boundary of the claimed design and do not form part of the claimed design. The longer dashed lines, such as the broken lines on the torso portion of the shirt and end portions of the sleeves of the shirt, or head of an example wearer, depict unclaimed environmental subject matter. The shorter dashed double lines represent seams that are a claimed surface pattern. The cross-hatching represents the position of a filter and/or filter holder.
